CLAIM

The ornamental design for a fashion belt, as shown and described.

DESCRIPTION

FIG. 1 is a front perspective view of the belt showing Applicant's new design;

FIG. 2 is a rear perspective view thereof;

FIG. 3 is a front elevational view thereof;

FIG. 4 is a rear elevational view thereof;

FIG. 5 is a right side elevational view thereof; and,

FIG. 6 is a left side elevational view thereof.

The dotted lines in FIGS. 2 and 4 depict stitching that forms no part of the claimed design. All other broken lines depict environment that forms no part of the claimed design.

1 Claim, 3 Drawing Sheets(56)
